UNITED STATES PATENT OFFICE.

FRANK P. HOWARD, OF SHERMAN, TEXAS.

ROPE-FASTENING DEVICE.

SPECIFICATION forming part of Letters Patent No. 645,100, dated March 13, 1900.

Application filed November 17, 1899. Serial No. 737,323. (No model.)

To all whom it may concern:

Be it known that I, FRANK P. HOWARD, a citizen of the United States, residing at Sherman, in the county of Grayson and State of 5 Texas, have invented a new and useful Rope-Fastening Device, of which the following is a specification.

This invention relates to rope-fastening devices, and is especially designed to connect 10 snap-hooks to the ends of ropes. It is furthermore designed to stiffen and protect the end of a rope and to provide means whereby a strain upon the rope will more firmly bind and clamp the same and without damage 15 thereto.

To these ends the present invention consists in the combination and arrangement of parts, as will be hereinafter more fully described, shown in the accompanying drawings, and particularly pointed out in the appended claims, it being understood that changes in the form, proportion, size, and the minor details may be made within the scope 25 of the appended claims without departing from the spirit or sacrificing any of the advantages of the invention.

In the drawings, Figure 1 is a side elevation of the rope-clamp, showing the initial position of the rope in the application of the 30 device. Fig. 2 is a sectional elevation showing the clamp secured to the rope. Fig. 3 is a detail view of the wire which is wrapped upon the rope.

Corresponding parts in the several figures 35 of the drawings are designated by like characters of reference.

Referring to the accompanying drawings, 1 designates a snap-hook having a spring-tongue 2 in engagement with the bill of the 40 hook and also provided with a longitudinally disposed tubular socket 3, which is located opposite the bill end of the snap-hook and is provided with a tapering bore 4, which decreases in diameter from the inner end to the 45 outer end thereof.

As illustrated in Fig. 1, a rope 5, to which the device is to be applied, is inserted into the tapering bore of the socket and through the inner larger end thereof, after which the 50 rope is drawn through the socket until but a few inches of the opposite end 6 remains at

the forward side of the device. A soft, preferably copper, wire 7, as best shown in Fig. 3, is then applied to the projecting end of the rope in the following manner: One end of 55 the wire is bent at substantially right angles thereto and formed into a pointed prong 8, which is driven transversely through the rope at a suitable distance from the adjacent extremity thereof and upset against the opposite side of the rope, as indicated at 9. The remaining portion of the wire is then wrapped tightly upon the rope and toward the adjacent extremity thereof, so as to form a spiral comprising the plurality of coils 10, which 60 firmly embrace the rope. After the wire has been thus wrapped upon the end of the rope the latter is drawn into the tapering bore of the socket, whereby the several coils bind upon the interior walls of the socket and are 65 forced into the rope, thereby wedging the latter within the socket and forming a tight and durable connection therewith. It will be noted that any strain upon the rope merely binds the socket more firmly thereon, and 70 the wire spiral protects the rope against damage by frictional contact with the walls of the socket.

By reference to Fig. 2 it will be seen that the outer or smaller end of the metallic socket 80 is beveled inwardly, as indicated at 11, so as to protect the rope against damage by engagement with this end of the socket during lateral movement thereof.

What is claimed is—

1. A rope-fastening device, comprising a metallic socket, having a tapering bore, and a rope received within the bore, and provided with a wrapping of wire, the latter adapted to bind against the walls of the bore and also 90 protect the rope.

2. A rope-fastening device, comprising a metallic tubular socket, having a tapering bore, a rope received within the bore, and a wire, having one end formed into a prong, 95 which is driven through the rope, and the remaining portion of the wire being formed into a spiral, to tightly embrace the rope and bind upon the walls of the bore.

3. The combination with a snap-hook, of a 100 tubular socket, located opposite the bill of the snap-hook, and extending longitudinally

thereof, said socket having a tapering bore, which decreases in diameter from the inner end of the socket, a rope received within the bore of the socket, and a wire wrapped upon the rope and adapted to bind upon the walls of the bore.

5 In testimony that I claim the foregoing as

my own I have hereto affixed my signature in the presence of two witnesses.

FRANK P. HOWARD.
